SCHOOL DESK

Gordon W. Florian, Fairfield, Harry W. Streck,
Bridgeport, and William E. Kelsey, Jr., Fair-
field, Conn.

Application April 15, 1952, Serial No. 19,336

Term of patent 3½ years

(Cl. D33—11)

To all whom it may concern:

Be it known that we, Gordon W. Florian, Harry W. Streck and William E. Kelsey, Jr., citizens of the United States and residents, respectively, of Fairfield, Bridgeport, and Fairfield, all in the county of Fairfield and State of Connecticut, have invented a new, original, and ornamental Design for School Desk, of which the following is a specification, reference being had to the accompanying drawings, forming part thereof.

In the drawings:

Fig. 1 is a front elevational view of a school desk, showing our new design;

Fig. 2 is a side elevational view;

Fig. 3 is a rear elevational view;

Fig. 4 is a bottom plan view;

Fig. 5 is a vertical sectional view, on an en-

larged scale, taken along the line 5—5 of Fig. 2.

We claim:

The ornamental design for a school desk, sub-
stantially as shown.

GORDON W. FLORIAN.
